VEHICLE FOR TRAVERSE ON A MONORAIL SYSTEM

William Muir Robb, West Drayton, England, assignor of one-half to Road Machines (Drayton) Limited, West Drayton, England, a British company

Application April 28, 1953, Serial No. 351,565

7 Claims. (Cl. 105—156)

This invention relates to an improved vehicle for traverse on a monorail system of the kind incorporating a pair of bogie units each having a track wheel for engagement with the rail.

The object of the present invention is to provide means whereby the vehicle is tilted inwardly relative to a curve in the track so as to improve the cornering characteristics of the vehicle.

The invention consists of a vehicle for traverse incorporating a pair of bogie units having track wheels for engagement with the rail characterised in that the bogie units are turnably mounted relative to the vehicle in such a manner that as the track wheels of the bogie units are turned out of alignment with the longitudinal axis of the vehicle to accommodate themselves to a curve in the rail a positive tilting of the vehicle about a longitudinal axis is effected automatically in an inward direction relative to the curve.

A convenient embodiment of the present invention will now be described in its application to a self-propelled vehicle and with reference to the accompanying drawings in which—

Fig. 1 is a side elevation of the vehicle which is illustrated engaged upon a part of a monorail track.

Fig. 2 is an enlarged plan of one end of the frame of the vehicle illustrating the manner of mounting a bogie unit within the frame.

Fig. 3 is a part section on the line 3—3 of Fig. 2 and

Fig. 4 is an end elevation of a bogie unit showing its engagement with the frame of the vehicle which is shown in section.

The body of the vehicle is shown diagrammatically at 5 and can desirably be side tipping. It is mounted upon a main frame 6 which extends beyond the body 5 and is connected at each end to a subsidiary frame 7. The main frame and subsidiary frames 6 and 7 are rigidly secured together and thus constitute a vehicle frame which has turnably mounted about a generally vertical axis a bogie unit. Each bogie unit incorporates a double flanged track wheel 8 which is adapted to engage the head of the rail 9 of a monorail system which may conveniently be of the kind described and illustrated in the specification of my co-pending patent application No. 351,564 filed April 28, 1953.

The track wheel 8 is rotatably mounted in bearings which are carried by a channel cross sectional circular frame 10 of the bogie, the channel whereof is directed outwardly and serves as a track in which engages two pairs of diametrically opposed flanged supporting rollers 11 and 12 which are rotatably mounted about fixed spindles carried by the subsidiary frame 7 and equally spaced apart around the circular frame 10. It will be appreciated that by virtue of this roller support of the circular frame 10, the bogie unit as a whole is rotatable about a generally vertical axis relative to the vehicle frame to admit of the track wheel 8 accommodating itself to a curve in the track. The diametrically opposed pair of rollers 12 which are situated in alignment with the

longitudinal axis of the vehicle are of a diameter such as to substantially fill the distance between the walls of the channel of the circular frame 10 so that the circular frame 10 is prevented from any tipping motion relative to the vehicle frame about an axis transverse thereto. The pair of diametrically opposed flanged rollers 11 are of a diameter approximately equal to half the distance between the walls of the channel of the circular frame 10 and when the track wheel 8 is in alignment with the longitudinal axis of the vehicle each of these rollers rests approximately mid-way upon the incline of an arcuate wedge block 13 secured to the lower wall of the channel of the circular frame 10. The pair of wedge blocks 13 are inclined in opposite directions relative to the direction of rotation of the circular frame 10 or, expressed in another manner, in the same direction relative to the longitudinal axis of the vehicle. When the circular frame 10 turns relative to the subsidiary frame 7 to permit the wheel 8 accommodating itself to a curve in the rail, the roller 11 on the outside of the bend will ride up the incline of its associated wedge block whilst the roller 11 on the inside of the bend will ride down the incline of its associated wedge block thereby effecting an automatic and positive tilting of the vehicle frame relative to the bogie in an inward direction relative to the curve.

Depending from the circular frame 10 on opposite sides of the rail 9 are a pair of channel cross section brackets 14 within each of which is pivotally suspended from the point 15 the upper end of an arm 16 carrying at its lower end a rotatable roller 17 which is adapted to ride against the foot of the rail 9. The rollers 17 are maintained in contact with the foot of the rail 9 by means of bonded rubber compression blocks interposed between the arms 16 and the brackets 14 and the compression whereof can be adjusted by means of set screws 18 in the brackets 14.

Also mounted on the underside of each frame 10 is a pair of rollers 19 engaging opposite sides of the head of the rail 9 immediately in front of the leading track wheel 8 and immediately behind the trailing track wheel 8, these rollers 19 in addition to enhancing the stability of the bogie on the track assist in the turning of the bogie unit relative to the vehicle frame to facilitate the wheel 8 accommodating itself to a curve in the rail.

The right hand bogie unit, as viewed in Fig. 1, has mounted thereon a self-contained motor and gear box for driving the track wheel 8, this mechanism being diagrammatically illustrated and designated by the reference 20.

I claim:

1. A vehicle for traverse on a monorail system where-in a pair of bogie units are turnable in a vehicle frame each of said bogie units having a section of track extending fore and aft on each side thereof, a roller engaging each such track section, said rollers being carried by said vehicle frame, said track sections having inclines extending upwardly toward the mid part of said vehicle frame to effect a positive tilting of the vehicle relative to the bogie units when the track wheels of the bogie units are turned out of alignment with the longitudinal axis of the vehicle.

2. A vehicle for traverse on a monorail system, said vehicle including a vehicle frame, a pair of wheeled bogie units each having a circular track of channel section, the channels of which open outwardly, two pairs of rollers carried by said vehicle frame and having the axes aligned with an axis about which the vehicle frame is tilttable, the rollers of each pair lying within the channel of one of said circular tracks, and two additional pairs of rollers carried by said vehicle frame, the rollers of each said additional pair being mounted on axes transverse to the axes of the first mentioned rollers, a pair of wedge blocks fixed within the channel of each of said circular tracks the wedge blocks of each pair having oppositely inclined

3

surfaces; the rollers of each said additional pair extending into the channel of one of said circular tracks and engaging the inclined surfaces of said wedge blocks, thus serving to control the extent of tilting said vehicle frame.

3. A vehicle for traverse on a monorail system, said vehicle including a vehicle frame, a pair of wheeled bogie units each having a circular track of channel section, the channels of which open outwardly, two pairs of rollers carried by said vehicle frame and having the axes aligned with an axis about which the vehicle frame is tiltable, the rollers of each pair lying within the channel of one of said circular tracks, and two additional pairs of rollers carried by said vehicle frame, the rollers of each said additional pair being mounted on axes transverse to the axes of the first mentioned rollers, the rollers of each said additional pair extending into the channel of one of said circular tracks and serving to control the extent of tilting said vehicle frame, wedge blocks fixed within the channels of said circular tracks, the wedge blocks within each channel having oppositely inclined surfaces the rollers of each of said additional pairs engaging the inclined surfaces said wedge blocks and cooperating therewith to tilt said vehicle frame.

4. A vehicle for traverse on a monorail system wherein a pair of bogie units are turnable in a vehicle frame, each of said bogie units having a section of track extending fore and aft on each side thereof, a roller engaging each such track section, said rollers being carried by said vehicle frame, said track sections having inclines extending upwardly toward the mid part of said vehicle frame to effect a positive tilting of the vehicle relative to the bogie units when the track wheels of the bogie units are turned out of alignment with the longitudinal axis of the vehicle, each bogie unit being provided with a pair of rollers for engagement on opposite sides of a rail of such monorail system.

5. A vehicle for traverse on a monorail system wherein a pair of bogie units are turnable in a vehicle frame, each of said bogie units having a section of track extending fore and aft on each side thereof, a roller engaging each such track section, said rollers being carried by said vehicle frame, said track sections having inclines extending upwardly toward the mid part of said vehicle frame to effect a positive tilting of the vehicle relative to the bogie units when the track wheels of the bogie units are turned out of alignment with the longitudinal axis of the vehicle, each bogie unit being provided with a pair of rollers for engagement on opposite sides of a rail of such monorail system.

system, each bogie unit having a flanged wheel rollable along such rail, the last mentioned rollers being located respectively ahead of the leading flanged wheel and behind the trailing flanged wheel.

5 6. A vehicle for traverse on a monorail system wherein a pair of bogie units are turnable in a vehicle frame, each of said bogie units having a section of track extending fore and aft on each side thereof, a roller engaging each such track section, said rollers being carried by said vehicle frame, said track sections having inclines extending upwardly toward the mid part of said vehicle frame to effect a positive tilting of the vehicle relative to the bogie units when the track wheels of the bogie units are turned out of alignment with the longitudinal axis of the vehicle, each bogie unit being provided with a pair of rollers for engagement on opposite sides of a rail of such monorail system, each bogie unit having a flanged wheel rollable along such rail, the last mentioned rollers being located respectively ahead of the leading flanged wheel and behind the trailing flanged wheel, each bogie unit being equipped with a pair of stabilizing rollers.

10 7. A vehicle for traverse on a monorail system wherein a pair of bogie units are turnable in a vehicle frame, each of said bogie units having a section of track extending fore and aft on each side thereof, a roller engaging each such track section, said rollers being carried by said vehicle frame, said track sections having inclines extending upwardly toward the mid part of said vehicle frame to effect a positive tilting of the vehicle relative to the bogie units when the track wheels of the bogie units are turned out of alignment with the longitudinal axis of the vehicle, each bogie unit being provided with a pair of rollers for engagement on opposite sides of a rail of such monorail system, each bogie unit having a flanged wheel rollable along such rail, the last mentioned rollers being located respectively head of the leading flanged wheel and behind the trailing flanged wheel, each bogie unit being equipped with a pair of stabilizing rollers, and resilient means for urging said stabilizing rollers into yieldable engagement with an element extending along such monorail system.
